CLAIM

The ornamental design for a combination camping lantern and remote, as shown and described.

DESCRIPTION

FIG. 1 is a front perspective view of a combination camping lantern and remote, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the area labeled 8 in FIG. 1. The broken lines in the drawings illustrate the portions of the combination camping lantern and remote, which form no part of the claimed design.

The dot-dash broken lines framing portions of the claimed design are included for the purpose of illustrating enlargements, and form no part of the claimed design.

1 Claim, 8 Drawing Sheets
